BRUSH LIFTING DEVICE

Clarence Ringwald, Springfield, Ohio, assignor to
 Robbins & Myers, Inc., Springfield, Ohio, a corporation of Ohio

Application December 15, 1930
 Serial No. 502,339

20 Claims. (Cl. 172—279)

My invention relates to electric motors of the brush lifting type and a novel brush lifting mechanism therefor.

Brush lifting and short circuiting mechanisms for motors starting as repulsion motors and thereafter operating as induction motors are known. The brush lifting mechanism of my invention is disposed wholly at the commutator end of the motor and hence rods, or other operating devices extending through the armature are not required.

In accordance with my invention the brush lifting and short circuiting mechanism is a compact assembly, easily applied to the motor and readily adjustable for setting the brushes at such position as will secure rotation in either direction. A mechanism of this class requires a non-rotating guide for holding the brush carrier in proper position relative to the commutator during starting and to guide it back out of the way when the brushes are lifted and the short circuiting mechanism operated.

According to my invention the guiding mechanism comprises a plate adjustably secured to the end frame of the motor, with two pins extending parallel to the axis of the shaft and extending into sleeves forming a part of the brush carrier frame, which brush carrier frame is thereby supported and guided. I dispose the centrifugal mechanism directly upon the shaft and radially inside the guiding pins.

The centrifugal mechanism comprises a pair of weights adapted to be thrown out by centrifugal force against the tension of a pair of springs upon the attainment of a predetermined speed which is considerably higher than the speed at which the weights will again be retracted.

The brushes are applied to the commutator through the action of the springs which govern the centrifugal weights. The entire brush frame and brushes have no bias, i. e., no spring loading of their own and hence there is required no end bearing under constant wear.

The frame of the centrifugal mechanism is a generally rectangular stamping which is light and inexpensive. Likewise, the centrifugal weights and arms are simple stampings. The springs are light coil springs placed in tension. These springs are light and strong and readily replaceable. The entire mechanism is unusually compact, inexpensive and highly effective. It is readily accessible for inspection.

Now in order to acquaint those skilled in the art with the manner of constructing and operat-

ing a device embodying my invention I shall describe, in connection with the accompanying drawings, a specific embodiment of the same.

In the drawings:

Figure 1 is a side elevation, partly in section, 60 of a motor embodying my invention;

Figure 2 is a fragmentary section taken on the line 2—2 of Figure 3, through the brush lifting device and commutator;

Figure 3 is a cross sectional view taken on the 65 line 3—3 of Figure 2;

Figure 4 is a side elevational view of the inertia or centrifugal mechanism;

Figure 5 is an end view of the same, taken 70 from the right of Figure 4; and

Figure 6 is a fragmentary view, illustrating the connection of the spring to the inertia lever.

Referring first to Figure 1, the motor herein shown comprises the field laminations 1 and armature laminations 2, of known form, these parts in an A. C. motor being generally termed stator and rotor, respectively. The stator laminations are confined between a flange 3, formed on one end of the cylindrical tubing shell 4 and a filler sleeve 5, which is held in place by flanging the opposite end of the sleeve 4, as indicated at 6. The opposite ends of the sleeve 4 are finished off as indicated at 7—8, to provide surfaces which are concentric with the inner face 9 of the laminations 1. These concentric cylindrical surfaces 7 and 8 are adapted to receive the rims or flanges 10 and 12 of the end frames or housings 13 and 14. These end frames 13—14 support bearings 15 and 16, having suitable bushings 17 and 18 of anti-friction metal cooperating with round cylindrical bearing portions of the motor shaft 19. The bearing boxes 15 and 16 embody suitable oil pockets such as that shown at 20 at the left of Figure 1. Oiler rings 22 dip into the lubricant in the pocket 20 and ride upon the bearing portion such as 23 through a slot in the anti-friction sleeve 17, as indicated at 24. The outer end of the journal box is closed by a metal cap 25 pressed in place to exclude dust and to assist in draining the lubricating medium back to the pocket 20 as through the passageway 26. At the opposite end of the journal box 15 a similar flanged pressed ring 27, which is adapted to retain a felt washer, if so desired, prevents the entry of dust into the bearing from the inner end and the felt washer (not shown) fits closely about the collar 28 which is mounted upon the shaft as will be more fully described hereinafter. It also assists in returning any excess lubricant to the pocket 20 through 100

105

110

115

120

125

the drain passageway 29. A vertical opening 30 at the top of the journal box 15 is closed as by means of a flanged sheet-metal plug 32 and in the center of the same an oiling thimble 33, provided with a snap cover, permits of the introduction of oil into the bearing and into the pocket 20. The journal box 15 has a concentric cylindrical boss 34 which seats in a concentric opening in the end frame 13. It will be observed that the end wall 35 of the end frame 13 lies in a plane transverse to the axis of the shaft 19, providing a flat clamping face on its inner surface for the rocker plate 36 which forms a part of the mechanism for changing the motor over from a repulsion motor to an induction motor. The boss 34 terminates in a suitable annular shoulder which engages the margin of the flat end portion 35 about the central opening and the journal box 15 is suitably secured to the flat plate portion 35 as by a filleted weld or the like.

The motor casing is formed of the central ring or sleeve 4 and the end frames 13 and 14 is, in the particular form shown in Figure 1, mounted upon a base comprising the base plate 37 and the brackets 38 and 39. These brackets 38 and 39 are formed of pieces of channel shaped sheet metal, or of structural channel. A U-shaped clamp 40 has its ends hooked or curved, as indicated at 42, about the bosses 43 which are secured to the bearing boxes 15 and 16 to support said bearing boxes directly from the base through the brackets 38 and 39.

The outer end of the shaft 19 is slabbed off, as indicated at 44, beyond the flanged retainer ring 45 which supports a suitable felt ring therein (not shown). The motor herein shown is of the so-called brush lifting type which starts as a repulsion motor and after being brought to substantially synchronous speed changes over from the repulsion type to the induction type by the operation of a short circuiting device which closes the windings together in closed loops. The windings (not shown) are connected to the bars of the commutator 46, this commutator, as shown in Figure 1, comprising a body 47 of metal or of insulation having a flange portion 48 and a hub portion 49, with a cylindrical recess 50 adjacent the hub portion 49. The commutator bars 52 have radial faces 53 and cylindrical faces 55 registering with the cylindrical walls of the recess 50. The commutator bars 52 are held together by a wedge ring 56, suitably held in place by countersunk screws 57 passing through the flange portion 48 and into said wedge ring 56. The wedge ring 56 may be formed of one or more parts for convenience in assembling. The flange portion 48 has a confining flange 58 at its outer end for retaining the wedge ring 56 against outward movement. Pre-formed sheets of insulating material 59 and 60, respectively, surround the wedge ring 56 and extend outwardly to separate the commutator body or base 46 from the segments 52. Preferably the base 46 is made of metal for the sake of strength and also to assist in short circuiting the commutator segments through the action of the short circuiting band spring 62. The windings of the rotor 2 are connected to the commutator segments 52 in well known manner to provide open windings which are closed by the short circuiting band spring 62, as will be described later.

In the present motor four composition brushes 63—63 are provided, these brushes being con-

nected together in pairs by means of stranded copper leads or pigtails 64—64 (see Figure 3). These metal pigtails serve the dual purpose of electrically connecting the brushes and also of preventing the brushes from projecting from the brush holders more than a predetermined distance. The brushes are placed at 90° from each other about the periphery of the commutator and are held in suitable brush holders 65 which are formed integrally with the central plate or hub portion 66. This plate or hub portion is provided with a central circular opening to be supported concentric with the axis of the shaft 19. The bore of the hub portion 66 is machined as likewise are the end faces adjacent the bore. The central bore of the hub portion 66 is machined concentric with the axis of the shaft 19 and the opposite faces of the margins of the hub are machined off in parallel planes, this hub portion being confined in a groove formed upon the shifter sleeve 67. Each brush holder 65 comprises a generally rectangular sleeve broached out to provide a suitable guide for the cooperating brush 63. Outwardly extending parallel flanges 68—68 are formed integral with the brush holder 65 and these flanges 68—68 form ears for a hinge pin 69 which is preferably riveted at its ends outside the ears 68—68, serving as a pivot or pintle for the brush follower levers 70. A coiled wire spring 72 loosely embraces the pin 69 and has one end thereof, as indicated at 73, bearing against the outside of the brush holder 65 and the opposite end thereof, as indicated at 74, (see Figure 2), bearing against the brush follower lever 70, 110 tending to press the brush towards the commutator. The follower lever is provided with a rear arm or portion 75 for rotating the arm 70 against the spring 72 so that the follower 70 may clear the brushes for removal of the brushes 115 from the brush holders. The longer arm 76 has its outer end recurved to provide a rounded cylindrical contact portion for engaging the back of the brush 63. The ears 68 are spaced apart a distance which is greater than the width of the 120 slot in the brush holder 65 and the lever 70 is wider than the slot so that the edges of the follower arm 76 are limited by engagement of the curved end with the edges of the holder 65.

The brush holder frame 61 is mounted and 125 supported independently of the shifter sleeve 67. The means for providing this support include integral bosses 77 formed as a part of the casting of which the brush holder frame 61 is composed, these bosses being bored out to receive 130 sleeves 78 of insulation which are pressed into the bores of the bosses 77. These bosses 77 are preferably disposed diametrically at opposite sides of the brush holder frame 61. The sleeves 78 in turn are mounted upon cylindrical pins 135 79—79 which pins are rigidly secured to the rocker plate 36. The bosses 77 are joined to the adjacent brush holders 65—65 by integral webs 80—80, which thereby not only connect the bosses 77 with the hub portion 66 of the brush holder frame but also serve to strengthen and brace together adjacent pairs of brush holders. The rocker plate 36 comprises a generally rectangular plate of metal modified, however, by having arcuate slots 82—82 at the opposite corners as is clearly shown in Figure 3, these slots permitting angular adjustment of the plate 36. The other corners of the plate 36 are offset to provide ears 84, the ears being perforated to receive the reduced ends 85 of the pins 79 and 140

the extreme outer ends of the pins 79 are riveted over as indicated at 86 so that the said guide pins 79 are rigidly connected to the plate 36. The offset ears 84 prevent the riveted ends 86 from engaging the end plate 35. Bolts 88, provided with suitable exterior clamping nuts 89 extend through the slots 82-82 and serve to clamp the main flat body portion of the plate 36 against the end plate 35.

10 Suitable indicia, for example, notches 90-90 are marked upon the plate 36, these notches being adapted to register with cooperating marks on the plate 35.

15 The slots 82-82 are so arranged that the rocker plate 36 may be shifted to sufficient angles to cause the motor to start in one direction or the other, as desired.

20 The shifter sleeve 67 is adapted to be shifted from the position shown in Figures 1 and 2 when the parts are at rest, towards the right when the motor is brought to substantially synchronous speed, through the operation of a suitable centrifugal mechanism 92 which is shown more in detail in Figures 4, 5 and 6. The sleeve 25 67 is relieved at its central part to facilitate endwise shifting upon the portion of the shaft lying between the shoulder 93 and the hub 49 of the commutator. At the right hand end of the sleeve 67 a groove 94, relatively wide and shallow, is provided in the said sleeve and the short circuiting band 62 is disposed in said groove. This short circuiting band comprises a helically wound spring, preferably made of wire either round in section or oblong in section, 30 having the ends of the coils substantially parallel with the radial faces of the groove 94 so that the spring band 62 may readily be shifted endwise of the shaft 19. The central part of the coils are deformed by being depressed inwardly 35 towards each other, leaving the rounded end portions 95-95 of relatively limited area but of considerable resiliency, whereby they are adapted to bridge the insulating plate 60 which lies between the commutator bars and the body 40 of the commutator supporting frame 47.

45 At its opposite end the shifter sleeve 67 is provided with a pair of parallel transverse grooves 96-96 for receiving the shifter pins 97 which lie parallel to each other on opposite sides of the shaft 19.

50 The inertia, or centrifugal mechanism is adapted to swing the pins 97 about the pivots or pivots 98 to shift the sleeve 67 to the left, as viewed in Figures 1 and 2. The connection between the shifter sleeve and the brush holder frame is provided by forming a shoulder 99 upon the left hand end of the sleeve adjacent the slots 96-96 and a groove 100 into which there is adapted to be seated a snap spring 55 ring 102, of wire or the like. A thin steel washer 103, relatively closely embraces the sleeve 67 and is retained by the snap, or spring ring 102. A washer 104 of bakelized fabric or bakelized fibre or the like is interposed between the steel washer 103 and the hub 66 of the brush holder frame. This washer 104 fits relatively closely on the cylindrical part of the sleeve 67. A ring 105 of similar insulation embraces the sleeve 67 and lies within the hub 66.

60 Upon the opposite side of the hub from the ring 104 a washer of similar insulation 106 embraces the sleeve 105. A steel washer 107 backs the insulating washer 106 and is interposed between the said insulating washer 106 and the shoulder 99. If desired, a thin steel washer 108 may be

interposed between the insulating washer 104 and the hub 66 to reduce wear.

65 The hub 66 is, by means of these washers and the sleeve 105, insulated from the shifter sleeve 67.

70 The inertia, or centrifugal mechanism which shifts the sleeve 67 and thereby the brushes 63 and the short circuiting ring 62, is shown more in detail in Figures 4, 5 and 6.

75 This mechanism comprises the collar 28 which is fixed upon the reduced portion 23 of the shaft 19 as by means of a pair of set screws 109 arranged at suitable parts of the periphery of the collar, for example, at 90° to each other. This collar supports a transverse sheet metal plate 110 which is secured to the said collar as by riveting, welding or the like. In the form shown the collar 28 is provided with a reduced neck 112 having a shoulder at one side and having the neck riveted over at the opposite side so as to grip the plate 110 firmly.

80 The plate 110 is generally rectangular in outline but it has the margins at opposite sides bent up at right angles to the body of the plate as shown at 113 in Figures 4 and 5 to provide 100 flanges, which flanges are cut out to provide the pivot ears 114, four in number, at each end of the flange 113. Between each pair of ears formed on the flange 113 there is provided a guard or retaining ear 115 which is curved 105 around the central part of the corresponding tension spring 116 to prevent the central part of such spring from flying out radially under centrifugal stress.

85 The shifting pins 97-97 are riveted, or otherwise fixed at their opposite ends in companion levers 117 which are formed as U-shaped stampings, the joining bar, or bottom of the U by which pairs of levers 117 are integrally joined, being plainly shown in elevation in Figure 5. If it is desired to increase the weight of the bar 118 an additional flat bar such as that shown at 119 in Figure 2 may be riveted to the bar 118.

90 The levers 117 are in effect bell crank levers, 120 comprising the shifter arm 120 and the inertia arm 122, the inertia arm in each case having the bar 118 joined thereto. The pivot or fulcrum on the pin 98 is disposed radially beyond the arms 120 and 122 and it may be seen, therefore, that the 125 inertia weight 118 is least effective before the bell crank levers swing about their pivots 98 and are of substantially maximum effectiveness after the inertia weights have caused the levers to move and to shift the shifter sleeve 67 to the right as 130 viewed in Figures 1 and 2. The outward motion of the inertia weight is checked by the limitation of the motion of the sleeve 67. The shifter sleeve 67 can travel only from the position shown in Figures 1 and 2 to the left until the sleeve engages 135 the buffer 123, which buffer is a flanged sheet metal ring, the inwardly extending flange of the same embracing the reduced end 23 of the shaft 19 and resting against the shoulder 93. The cylindrical body of the ring 123 bears edgewise 140 against the plate 110 radially beyond the riveted neck 112. By means of the buffer ring 123 a suitable stop for the shifter sleeve 67 is provided and also the collar 28 is accurately spaced with respect to the shoulder 93 on the shaft 19. A felt 145 washer 125 is preferably interposed between the buffer ring 123 and the end of the shifting sleeve 67. Preferably an anti-friction washer of bakelized fabric or the like is located at 126 between the end of the collar 29 and the bearing bushing 150

17. Likewise, one or more washers may be interposed at 127 between the shoulder 128 at the opposite end of shaft 19 and the bearing bushing 18 of the bearing box 16. 80
18. 5 The bell crank levers 117, which are shown in elevation in Figure 1 are provided with short arms 129 lying, when the parts are in the position shown in Figures 1 and 2, radially beyond the pivot pins 98 and carrying spring mounting pins 130. These pins 130 extend between the arms 129 of companion levers 117 and project outwardly over the pivot ears 114 as plainly shown in Fig. 4 to limit the rotation of the levers 117 towards each other under the influence of the tension springs 116. The outer ends of the said pins 130 are provided with circumferential grooves and the springs 116 are provided with eyes which hook over the ends of the pins 130 and rest in the said grooves. The pins 130 are nubled or scored and pressed into the arms 129 so that they are thereby retained against movement by the locking action of the nubls 132 with the bore of the opening through the corresponding arm 129. 85
19. 15 The operation of the brush shifting and short circuiting mechanism is as follows: With the parts as shown in Figure 1 or 2 the springs 116 bring the pins 130 inwardly until they engage the pivot ears 114. This holds the inertia weight 20 such as 118 in their innermost position. The shifter arms 120 of the bell crank levers 117 have, through their connected shifter pins 97 and the slot 96, shifted the sleeve 67 to substantially the limit of movement inwardly or 25 to the right as viewed in Figures 1 and 2. At this time the short circuiting band 62 is housed entirely within the commutator frame away from the commutator segments. At the same time the brush holder frame is carried towards the commutator so that the brushes 63 engage the radial face of the commutator. The springs 116, operating through the leverage system, apply sufficient pressure to the brush holder frames to overcome the relatively light tension of the 30 brush follower springs 72, so that the brushes 63 are applied under a light, but sufficient spring pressure against the radial faces of the commutator bars. 35
- If now the stator 1 is energized by connecting 35 to a source of suitable single phase current, the leads for which may be led to the stator windings through the insulating sleeve 133, the rotor windings are energized. The present motor is provided with two pairs of poles and the brushes 40 are arranged to selectively short circuit the coils of the rotor through the commutator to cause the motor to start up as a repulsion type motor. As is well known, sufficient torque may be developed to start under fairly heavy load. 45 As the rotor approaches synchronous speed the centrifugal force developed by the bars 118 which form inertia, or centrifugal weights, becomes great enough to oppose the tension of the springs 116. Thereupon, the bell crank levers begin to rotate about the pivot pins 98 and as the effective lever arm of the inertia weight becomes greater and as the effective lever arm of the springs becomes less, the shifter sleeve 67 is quickly thrown, or snapped to the 50 left, as viewed in Figure 1 or 2. 55
- The rotation of the rotor drives the inertia, or centrifugal mechanism 92 by the grip which the collar 28 has upon the reduced portion 23 of the shaft 19, this being secured, primarily, by 60 the set screws 109. The grooves 96, in which the shifting pins 97 are arranged to play, are straight cross grooves and hence any tendency to cause rotation between the shifter sleeve 67 and the shaft 19 will be unable to effect the same, since the grooves 96 do not extend completely around the shifter sleeve 67. Also, the friction between the short circuiting band 62, the groove 94 on the one hand and the recess 50 on the other, tends to prevent such rotation. 65
- The brush holder frame 61 is held against rotation by the guiding pins 79 which are fixed on the rocker plate 36. 70
- As the shifter levers operate to carry the shifter sleeve 67 to the left, the shifter sleeve first carries the short-circuiting band across the plate of insulation 60 into engagement with the commutator segments 55, short circuiting the windings of the rotor 2 and causing the motor to continue to operate as an induction motor, and thereafter the brushes 63 are lifted or moved out of engagement with the commutator. This movement of the short circuiting band to short circuiting position first is accomplished by positioning of the short circuiting band for movement with the initial movement of the shifter sleeve 67 whereas the follower levers 70 tend to maintain the brushes 63 in engagement with the commutator at least momentarily or during the initial movement of the sleeve 67. The distance which the spring actuated brush follower levers 70 can follow the brushes is limited by the engagement of said levers 70 with the sides of the brush holder sockets, so that the brushes will be removed from engagement with the commutator segments and at the same time 100 wear between the brushes and commutator is reduced. 105
- It will be observed that the brush holder frame 61 is unbiased and has no tendency of its own to move the brushes against the commutator. The springs 116 are the springs which apply the brushes to the commutator and these springs are embodied in the centrifugal mechanism 92. As a result, there is no appreciable wear between the hub 66 of the brush holder frame 61 and the sleeve 67. Therefore, the brush holder frame 110 will assume a position on the guiding pins 79 where minimum friction with respect to the moving sleeve 67 occurs. 115
- Since the guarding ears 115 are located at the central parts of the springs they do not interfere with the effective and equal operation of the two ends of the springs. 120
- In Figure 2 I have shown a modified form of commutator. In this construction the commutator bars are recessed at their backs to receive an insulating ring 135. This ring has a series of counterbored holes for receiving mounting rivets. The double ended rivets 136 have collars at their central portion and one end of the rivet, in each case, is first spun or riveted through the hole in the ring 135 and then the commutator bars are mounted on said ring in spaced relation and held thereto as by means of the riveted pins 137. The insulating plate 60 is 130 then laid upon the back of the ring 135 and the cylindrical inner edges of the commutator bars and the inner ends of the rivets 136 are spun or riveted to the flange 48 of the commutator body or frame 47. 135
- This construction is optional. The specific form of the commutator is not involved in the present invention so long as it conforms to the requirements of the brush lifting and short circuiting mechanism heretofore described. 140
- 145

I do not intend to be limited to the details shown and described, except as they are recited in the appended claims.

I claim:

5. 1. In a mechanism of the class described, the combination with a motor shaft and end frame of a plate mounted on the end frame and adapted for angular adjustment relative thereto, guiding pins mounted on the plate, a brush holder frame sleeved on said pins for free endwise movement on said pins, a sleeve endwise shiftable on the shaft, a frame fixed on the shaft, shifter levers pivoted on said latter frame and having operating arms coupled to said sleeve and inertia arms and tension springs lying on opposite sides of the shaft connecting said levers to hold the inertia arms inwardly when the shaft is at rest, said sleeve and said brush holder frame being coupled together for endwise motion but being rotatable relative to each other. 80
10. 2. In combination, a shaft, a motor frame member, a centrifugal mechanism comprising levers having inertia arms mounted on the shaft, a shifting sleeve on the shaft coupled to said levers, a brush frame mounted on the sleeve for endwise motion therewith but free for relative rotation therebetween, and a non-rotatable guide disposed radially outside the centrifugal mechanism, said brush frame being slidably guided on said guide and brush means carried by said brush frame and movable into and out of engagement with the commutator. 85
15. 3. A guide frame for centrifugally operated brush holder frames comprising a plate having a central opening adapted to embrace a guiding hub and having an arcuate slot concentric with said opening, offset portions disposed about the margins of the plate and having openings therethrough, and shouldered pins riveted in 90
20. said openings, said pins extending parallel to the axis of said central opening and attached directly to said plate. 95
25. 4. In combination, a motor end frame having a bearing providing a hub and having a flat end wall, a guide frame comprising a flat plate having a central opening piloted on said hub, an arcuate slot adjacent the margin of the plate, a clamping bolt passing through said slot and through said flat end wall, a plurality of 100
30. offset ears on the margin of the plate and guide pins secured to said ears and extending parallel to the axis of said central opening, said guide pins being carried by said plate independently of the end wall of the motor frame and independently of said clamping bolt. 105
35. 5. In combination, a motor end frame having a bearing providing a hub and having a flat end wall, a guide frame comprising a flat plate having a central opening piloted on said hub, an arcuate slot adjacent the margin of the plate, a clamping bolt passing through said slot and through said flat end wall, a plurality of offset 110
40. ears on the margin of the plate, guide pins secured to said ears and extending parallel to the axis of said central opening, said guide pins being carried by said plate independently of the end wall of the motor frame and independently of said clamping bolt. 115
45. 6. In combination, a motor end frame having a bearing providing a hub and having a flat end wall, a guide frame comprising a flat plate having a central opening piloted on said hub, an arcuate slot adjacent the margin of the plate, a clamping bolt passing through said slot and through said flat end wall, a plurality of offset 120
50. ears on the margin of the plate, guide pins secured to said ears and extending parallel to the axis of said central opening, said guide pins being carried by said plate independently of the end wall of the motor frame and independently of said clamping bolt. 125
55. 7. In combination in a motor, a frame having end plates providing bearings, one of said bearings providing a piloting hub, a shaft mounted in the bearings, a commutator on the shaft comprising a base having a hub which is secured on the shaft, said base having a concentric cylindrical recess, metallic segments mounted in insulated relation on the base, said segments having radial faces adapted to be engaged by brushes and having a cylindrical inner face substantially registering with the surface of the recess, a rocker plate having an opening piloted on said piloting hub and adjustably clamped to the adjacent end plate, guiding rods mounted at one end on said rocker plate and extending parallel to the axis of the shaft, a brush holder frame sleeved on said rods, brushes for cooperation with the radial faces of the commutator segments carried by 130
60. said latter frame, a shifter sleeve slidably mounted on said shaft and having one end extended into said cylindrical recess, said end of the sleeve having a groove, a spring band mounted in said groove and adapted when the sleeve is shifted to be brought into contact with the cylindrical faces of said segments to short circuit the same, a centrifugal mechanism carried on said shaft and confined radially within said guiding rods, said latter mechanism comprising levers carrying inertia weights and having operating connections with said shifter sleeve, said brush holder frame embracing said sleeve and there being shoulders on the sleeve on each side of the shifter frame. 135
65. 8. In combination, a shaft, a collar on the shaft fixed thereto, a transverse plate mounted on said collar, said plate having pivot ears disposed in pairs on opposite sides of the shaft, said ears being disposed at right angles to the body of the plate and pairs thereof having pivot holes in alignment with each other, bell crank levers formed of U-shaped stampings having pivot holes disposed between pairs of ears, pivot pins extending through said aligned holes in the ears and in the bell cranks, the bottom of the U of each lever stamping providing an inertia weight, both arms of each bell crank lever extending inwardly from the pivots in said ears, the free ends of the U-shaped stampings being joined by transverse pins, said bell crank levers having arms disposed beyond said pivot openings, transverse pins extending between the arms, said pins at their ends extending out beyond the pivot ears, and a pair of tension springs connecting the outer ends of said last named pins, a sleeve on the shaft, said sleeve being grooved to receive the first named transverse pins. 140
70. 9. In combination, a shaft, a collar on the 145
75. 10. In combination, a shaft, a collar on the 150

- shaft fixed thereto, a transverse plate mounted on said collar, said plate having pivot ears disposed in pairs on opposite sides of the shaft, said ears being disposed at right angles to the 5 body of the plate and pairs thereof having pivot holes in alignment with each other, bell crank levers formed of U-shaped stampings having pivot holes disposed between pairs of ears, pivot pins extending through said aligned holes in 10 the ears and in the bell cranks, the bottom of the U of each lever stamping providing an inertia weight, both arms of each bell crank lever extending inwardly from the pivots in said ears, the free ends of the U-shaped stampings being 15 joined by transverse pins, said bell crank levers having arms disposed beyond said pivot openings, transverse pins extending between the arms, said pins at their ends extending out beyond the pivot ears, and a pair of tension 20 springs connecting the outer ends of said last named pins, a sleeve on the shaft, said sleeve being grooved to receive the first named transverse pins and switching means carried by said last named sleeve.
- 25 10. In combination, a shaft, a collar on the shaft fixed thereto, a transverse plate mounted on said collar, said plate having pivot ears disposed in pairs on opposite sides of the shaft, said ears being disposed at right angles to the 30 body of the plate and pairs thereof having pivot holes in alignment with each other, bell crank levers formed of U-shaped stampings having pivot holes disposed between pairs of ears, pivot pins extending through said aligned holes in 35 the ears and in the bell cranks, the bottom of the U of each lever stamping providing an inertia weight, both arms of each bell crank lever extending inwardly from the pivots in said ears, the free ends of the U-shaped stampings being 40 joined by transverse pins, said bell crank levers having arms disposed beyond said pivot openings, transverse pins extending between the arms, said pins at their ends extending out beyond the pivot ears, and a pair of tension 45 springs connecting the outer ends of said last named pins, a sleeve on the shaft, said sleeve being grooved to receive the first named transverse pins, said transverse plate having ears extending outside the central parts of said 50 springs to restrain the springs from being extended radially by centrifugal force.
11. In combination, a shaft, a collar fixed on the shaft, a transverse generally rectangular plate fixed to the collar, a shifter sleeve mounted on the shaft, said plate having pivot ears bent up along two opposite margins, said ears being apertured, pivot pins extending through the apertures of the ears and lying parallel to each other on opposite sides of the 55 shaft, four bell crank levers mounted on said pivot pins inside said ears and comprising inertia arms and operating arms, said levers having their pivotal portions disposed radially outermost so that the arms extend diagonally inwardly generally toward the shaft, the operating arms of each pair being joined by a transverse shifter pin, the inertia arms of each pair being connected together by a transverse inertia member, said shifter sleeve being grooved 60 to receive the shifter pins, said levers having outward extensions and spring anchor pins extending through said extensions and projecting across the edges of the ears and serving to limit the angular position of said levers, and tension 65 springs connected to the ends of said latter pins
- for holding the inertia arms inwardly, and a brush holder frame guided longitudinally of the shaft and coupled to said shifter sleeve.
12. In combination in a motor, a motor frame having end frames comprising bearings, a shaft extending through said bearings, one of said end frames having a flat internal clamping face and the bearing thereof having a piloting boss, a rocker guide plate having an opening piloted on said boss, and having an arcuate slot for angular adjustment about said boss, clamping means extending through said slot for clamping the guide plate against the clamping face of said end frame, guide rods fixed to said rocker plate, a brush holder sleeved on said rods, said shaft having a shoulder adjacent said bearing of said one end frame, a collar on said shaft, a transverse pivot plate secured to the end of said collar remote from said one bearing, a hollow spacer disposed between the shoulder on the shaft and said pivot plate, said pivot plate having integral pivot ears extending in parallel planes on each side of the shaft, U-shaped stampings providing loaded bell crank levers at their ends extending in planes parallel to the pivot ears and the pivotal portions of connected bell crank levers, shifter pins connecting the free ends of the bell crank levers, a shifter sleeve guided on the shaft and being grooved at opposite sides to receive the shifter pins, said pins preventing rotation between the sleeve and the shaft, coil springs lying outside the pivot ears and parallel thereto connecting the adjacent ends of said U-shaped stampings, said transverse plate having fingers extending around the outside of said springs along their central portions to prevent radially outward movement thereof due to centrifugal force. 90
13. In combination in a motor, a motor frame having end frames comprising bearings, a shaft extending through said bearings, one of said end frames having a flat internal clamping face and the bearing thereof having a piloting boss, a rocker guide plate having an opening piloted on said boss and having an arcuate slot for angular adjustment about said boss, clamping means extending through said slot for clamping the guide plate against the clamping face of said end frame, guide rods fixed to said rocker plate, a brush holder sleeved on said rods, said shaft having a shoulder adjacent said bearing of said one end frame, a collar on said shaft, a transverse pivot plate secured to the end of said collar remote from said one bearing, a hollow spacer disposed between the shoulder on the shaft and said pivot plate, said pivot plate having integral pivot ears extending in parallel planes on each side of the shaft U-shaped stampings providing loaded bell crank levers at their ends extending in planes parallel to the pivot ears and the pivotal portions of connected bell crank levers, shifter pins connecting the free ends of the bell crank levers, a shifter sleeve guided on the shaft and being grooved at opposite sides to receive the shifter pins, said pins preventing rotation between the sleeve and the shaft, coil springs lying outside the pivot ears and parallel thereto connecting the adjacent ends of said U-shaped stampings, said transverse plate having fingers extending around the outside of said springs along their central portions to prevent radially outward movement thereof due to centrifugal force. 100
14. In combination in a motor, a motor frame having end frames comprising bearings, a shaft extending through said bearings, one of said end frames having a flat internal clamping face and the bearing thereof having a piloting boss, a rocker guide plate having an opening piloted on said boss and having an arcuate slot for angular adjustment about said boss, clamping means extending through said slot for clamping the guide plate against the clamping face of said end frame, guide rods fixed to said rocker plate, a brush holder sleeved on said rods, said shaft having a shoulder adjacent said bearing of said one end frame, a collar on said shaft, a transverse pivot plate secured to the end of said collar remote from said one bearing, a hollow spacer disposed between the shoulder on the shaft and said pivot plate, said pivot plate having integral pivot ears extending in parallel planes on each side of the shaft U-shaped stampings providing loaded bell crank levers at their ends extending in planes parallel to the pivot ears and the pivotal portions of connected bell crank levers, shifter pins connecting the free ends of the bell crank levers, a shifter sleeve guided on the shaft and being grooved at opposite sides to receive the shifter pins, said pins preventing rotation between the sleeve and the shaft, coil springs lying outside the pivot ears and parallel thereto connecting the adjacent ends of said U-shaped stampings, said transverse plate having fingers extending around the outside of said springs along their central portions to prevent radially outward movement thereof due to centrifugal force, a commutator having segments provided with a radial face and an internal cylindrical face, said shifter 110
15. In combination in a motor, a motor frame having end frames comprising bearings, a shaft extending through said bearings, one of said end frames having a flat internal clamping face and the bearing thereof having a piloting boss, a rocker guide plate having an opening piloted on said boss and having an arcuate slot for angular adjustment about said boss, clamping means extending through said slot for clamping the guide plate against the clamping face of said end frame, guide rods fixed to said rocker plate, a brush holder sleeved on said rods, said shaft having a shoulder adjacent said bearing of said one end frame, a collar on said shaft, a transverse pivot plate secured to the end of said collar remote from said one bearing, a hollow spacer disposed between the shoulder on the shaft and said pivot plate, said pivot plate having integral pivot ears extending in parallel planes on each side of the shaft U-shaped stampings providing loaded bell crank levers at their ends extending in planes parallel to the pivot ears and the pivotal portions of connected bell crank levers, shifter pins connecting the free ends of the bell crank levers, a shifter sleeve guided on the shaft and being grooved at opposite sides to receive the shifter pins, said pins preventing rotation between the sleeve and the shaft, coil springs lying outside the pivot ears and parallel thereto connecting the adjacent ends of said U-shaped stampings, said transverse plate having fingers extending around the outside of said springs along their central portions to prevent radially outward movement thereof due to centrifugal force, a commutator having segments provided with a radial face and an internal cylindrical face, said shifter 120
16. In combination in a motor, a motor frame having end frames comprising bearings, a shaft extending through said bearings, one of said end frames having a flat internal clamping face and the bearing thereof having a piloting boss, a rocker guide plate having an opening piloted on said boss and having an arcuate slot for angular adjustment about said boss, clamping means extending through said slot for clamping the guide plate against the clamping face of said end frame, guide rods fixed to said rocker plate, a brush holder sleeved on said rods, said shaft having a shoulder adjacent said bearing of said one end frame, a collar on said shaft, a transverse pivot plate secured to the end of said collar remote from said one bearing, a hollow spacer disposed between the shoulder on the shaft and said pivot plate, said pivot plate having integral pivot ears extending in parallel planes on each side of the shaft U-shaped stampings providing loaded bell crank levers at their ends extending in planes parallel to the pivot ears and the pivotal portions of connected bell crank levers, shifter pins connecting the free ends of the bell crank levers, a shifter sleeve guided on the shaft and being grooved at opposite sides to receive the shifter pins, said pins preventing rotation between the sleeve and the shaft, coil springs lying outside the pivot ears and parallel thereto connecting the adjacent ends of said U-shaped stampings, said transverse plate having fingers extending around the outside of said springs along their central portions to prevent radially outward movement thereof due to centrifugal force, a commutator having segments provided with a radial face and an internal cylindrical face, said shifter 130
17. In combination in a motor, a motor frame having end frames comprising bearings, a shaft extending through said bearings, one of said end frames having a flat internal clamping face and the bearing thereof having a piloting boss, a rocker guide plate having an opening piloted on said boss and having an arcuate slot for angular adjustment about said boss, clamping means extending through said slot for clamping the guide plate against the clamping face of said end frame, guide rods fixed to said rocker plate, a brush holder sleeved on said rods, said shaft having a shoulder adjacent said bearing of said one end frame, a collar on said shaft, a transverse pivot plate secured to the end of said collar remote from said one bearing, a hollow spacer disposed between the shoulder on the shaft and said pivot plate, said pivot plate having integral pivot ears extending in parallel planes on each side of the shaft U-shaped stampings providing loaded bell crank levers at their ends extending in planes parallel to the pivot ears and the pivotal portions of connected bell crank levers, shifter pins connecting the free ends of the bell crank levers, a shifter sleeve guided on the shaft and being grooved at opposite sides to receive the shifter pins, said pins preventing rotation between the sleeve and the shaft, coil springs lying outside the pivot ears and parallel thereto connecting the adjacent ends of said U-shaped stampings, said transverse plate having fingers extending around the outside of said springs along their central portions to prevent radially outward movement thereof due to centrifugal force, a commutator having segments provided with a radial face and an internal cylindrical face, said shifter 140
18. In combination in a motor, a motor frame having end frames comprising bearings, a shaft extending through said bearings, one of said end frames having a flat internal clamping face and the bearing thereof having a piloting boss, a rocker guide plate having an opening piloted on said boss and having an arcuate slot for angular adjustment about said boss, clamping means extending through said slot for clamping the guide plate against the clamping face of said end frame, guide rods fixed to said rocker plate, a brush holder sleeved on said rods, said shaft having a shoulder adjacent said bearing of said one end frame, a collar on said shaft, a transverse pivot plate secured to the end of said collar remote from said one bearing, a hollow spacer disposed between the shoulder on the shaft and said pivot plate, said pivot plate having integral pivot ears extending in parallel planes on each side of the shaft U-shaped stampings providing loaded bell crank levers at their ends extending in planes parallel to the pivot ears and the pivotal portions of connected bell crank levers, shifter pins connecting the free ends of the bell crank levers, a shifter sleeve guided on the shaft and being grooved at opposite sides to receive the shifter pins, said pins preventing rotation between the sleeve and the shaft, coil springs lying outside the pivot ears and parallel thereto connecting the adjacent ends of said U-shaped stampings, said transverse plate having fingers extending around the outside of said springs along their central portions to prevent radially outward movement thereof due to centrifugal force, a commutator having segments provided with a radial face and an internal cylindrical face, said shifter 150

- sleeve having a groove, and a coil spring of toroidal form disposed in said latter groove and being adapted to engage the cylindrical surface of said segments when the shifter sleeve is shifted by said shifter pins. 5
14. In combination in a motor, a motor frame having end frames comprising bearings, a shaft extending through said bearings, one of said end frames having a flat internal clamping face and the bearing thereof having a piloting boss, a rocker guide plate having an opening piloted on said boss and having an arcuate slot for angular adjustment about said boss, clamping means extending through said slot for clamping 10 the guide plate against the clamping face of said end frame, guide rods fixed to said rocker plate, a brush holder sleeved on said rods, said shaft having a shoulder adjacent said bearing of said one end frame, a collar on said shaft, a transverse pivot plate secured to the end of said collar remote from said one bearing, a hollow spacer disposed between the shoulder on the shaft and said pivot plate, said pivot plate having integral pivot ears extending in 15 parallel planes on each side of the shaft, U-shaped stampings providing loaded bell crank levers, said levers extending in planes parallel to the pivot ears, pivot pins passing through the ears and the pivotal portions of connected bell crank levers, shifter pins connecting the free ends of the bell crank levers, a shifter sleeve guided on the shaft and being grooved to receive the shifter pins, said pins preventing rotation between the sleeve and the shaft, coil 20 springs lying outside the pivot ears and parallel thereto and connecting said U-shaped stampings, said transverse plate having fingers extending around the outside of said springs along their central portions to prevent said springs being extended by their own centrifugal force, a commutator having segments provided with a radial face and an internal cylindrical face, said shifter sleeve having a groove, and a coil spring band disposed in said latter groove and being adapted to engage the cylindrical surfaces 25 of said segments when the shifter sleeve is shifted by said shifter pins, said brush holder having a central hub portion provided with an aperture passing over said shifter sleeve, said shifter sleeve having a shoulder lying on one side of the hub portion of the brush holder and a groove upon the other side thereof, and a snap ring in the groove for holding the shifter sleeve and the brush holder together for end- 30 wise motion but permitting rotative motion. 55
15. In combination with a commutator having segments provided with radial faces and internal cylindrical faces of a short circuiting means comprising a sleeve having a relatively wide shallow groove and a band shaped coil spring the median parts of the coils of which are offset toward each other, leaving enlarged portions at the end of each coil which are relatively freely expandible and compressible radially of the sleeve to make good short-circuiting contact with the cylindrical surface of said segments, a motor shaft, said sleeve having a second groove and centrifugal means including a shifting lever having a pin lying in a direction generally across the axis of the motor shaft and engaging in said second groove. 60
16. In combination, a brush supporting frame comprising a central hub portion having a central bore and integral brush holders having oblong bores therethrough parallel to the central 65
- bore, ears extending outwardly from said brush holders, brush follower levers pivoted between said ears, springs disposed about the pivots of said levers for urging the ends of the levers toward the sockets, mounting sleeves having bores the axes of which are parallel to the axis of the central bore and upon opposite sides of the same, said sleeves being attached to the hub by webs joining adjacent brush holders. 80
17. In combination, a brush supporting frame comprising an apertured hub portion and peripherally disposed brush holding sockets open at both ends, integral guiding sleeves on the hub portion, stationary guide rods extending through said sleeves and a shifter sleeve having shoulders on opposite sides of the hub for shifting the brush supporting frame on said guide rods. 85
18. In combination, a rotatable shaft having a reduced portion and a main portion with a shoulder between them, a collar fixed upon the reduced portion, a transverse frame plate secured upon one end of the collar, shifter levers having inertia arms, springs for said levers, said levers being pivoted on said frame plate, a shifter sleeve slidable on the main portion of 90 said shaft, shifter pins connecting the levers and the sleeve, a buffer collar of a diameter greater than the diameter of the main portion of the shaft lying between the said shoulder and said frame plate and adapted to be engaged by 95 the sleeve when the shifter levers are actuated by the inertia arms. 100
19. A centrifugal switching device comprising a rotatable shaft, a stationary guide parallel to the shaft, a frame non-rotatably guided along 110 said guide, said frame carrying an electric contact, a collar on the shaft, a transverse plate on said collar, said plate having pivot ears disposed in parallel planes upon opposite sides of the shaft, U-shaped stampings comprising 115 each a transverse joining portion providing an inertia member, and bell crank levers disposed in parallel planes to said pivot ears, pivot pins in said pivot ears extending parallel to said transverse plate and passing through the said bell crank levers, said bell crank levers having inertia arms joined by said inertia member and free arms having shifter pins, and a shifter sleeve for shifting said frame, said sleeve being disposed on said shaft and having grooves for 120 receiving said shifter pins. 125
20. A centrifugal switching device comprising a rotatable shaft, a transverse plate mounted non-rotatably on the shaft, said plate having integral pivot ears at its opposite margins disposed in parallel planes upon opposite sides of the shaft, a pair of U-shaped stampings each comprising a transverse joining portion providing an inertia member, and bell crank levers disposed in parallel planes adjacent the pivot 130 ears, pivot pins extending through the ears and the levers, said pins lying substantially in a common plane parallel to said plate, said levers having inertia arms joined by said inertia members and free shifter arms provided with shifter 135 pins, a shifter sleeve on the shaft, said sleeve being grooved to receive said pins, and electric switching means actuated by shifting of said shifter sleeve. 140

CLARENCE RINGWALD. 135
